UNITED STATES PATENT OFFICE.

JOHN THOMAS McGRATH, OF BLOOMINGTON, ILLINOIS.

CLAMP FOR ROTARY CAN OPENERS.

Application filed August 6, 1921. Serial No. 490,430.

This invention relates to improvements in can openers, and refers more particularly to a machine of the rotary type in which the cutting knife is supported and designed to be revolved over the can head in circular alignment with the coacting zone of the head at which the head is to be cut. The machine shown is particularly adapted for heavy duty work, as in restaurants, hotels, for opening paint cans, and the like, although it can be employed for lighter domestic work.

A can opening machine embodying my invention embraces means for holding and locking a can in position, and preferably designed to receive and hold cans of different diameters, combined with a revolving cutter suitably supported to act on the head of a can thus supported for severing and removing all or a portion of the head, the cutter being mounted and adapted to be revolved about the axis of the can at a desirable distance from the lock seam that connects the head with the body.

Among the objects of the invention is to provide a simple and efficient can opener of this type adapted to quickly receive and lock therein a can to be opened, and provided with a revolving knife which acts upon the can when thus held stationary to quickly travel about a line at a predetermined distance from the margin of the head to wholly or partially sever the head.

Another object of the invention is to provide a novel support and locking means designed to quickly adjust the holder to cans of varying diameters and to lock the cans rigidly in place with respect thereto.

Other objects of the invention are to further improve and simplify can opening machines of this general character, and the invention consists in the combination and arrangement of the parts shown in the drawings and described in the specification, and is pointed out in the appended claim.

In the drawings:

Figure 1 is a side view of a can opening machine embodying my invention, showing in section the table or support to which it is attached.

Figure 2 is an end view, on an enlarged scale, of the knife and its carrier.

Figure 3 is a section on the line 3—3 of Figure 1.

Figure 4 is a section on the line 4—4 of Figure 1, with parts shown in elevation.

Figure 5 is a partial plan and horizontal sectional view, on the line 5—5 of Figure 1.

Figure 6 is a vertical section on the line 6—6 of Figure 5.

Figure 7 is a plan view of a clutch jaw operating disc.

Figure 8 is a plan view of a clutch jaw guide.

Figure 9 illustrates a portion of the locking means for locking in position the parts which adapt the machine to cans of different heights.

As shown in the drawings, 10 designates a post or standard having a reinforcing rib 11 and parallel beveled guide and gripping faces 12. 13 designates a bracket which is adapted to sustain the can support on which the can is centered and locked while the head is being cut. It is formed at one end with vertically arranged jaws 14, 14 (Figures 1 and 5) that are provided with opposing undercut or angular grooves 15 to fit over the beveled guiding and locking edges 12 of the post. Said jaws are adapted to be pressed against said beveled or locking edges by means of a screw bolt 17, the threaded end 18 of which engages a threaded opening of one of the jaws 14. The other end of the bolt extends loosely through an opening in the opposite jaw which registers with said threaded opening. To clamp said jaws on the post the screw 17 is turned to lock the inclined faces of the jaws and post firmly together, and final locking pressure is exerted on said jaws through the medium of a cam lock which embraces a lever 20 that has a forked end and is hinged at its forked end, as by a pin 21, to the adjacent end of the screw 17.

The forks of said lever are formed with cam portions 22 which are adapted, when the lever is swung inwardly towards and against the adjacent jaw 14, to be pressed against a face or pad 23 of the adjacent jaw to exert final pulling stress on the locking bolt 17. When this form of screw thread and cam lock are employed, the lever 20 can be swung out in line with the bolt 17 when the latter is being turned to effect preliminary clamping pressure of the jaws on the post, and, therefore, when said lever is swung downwardly, the cam portion 22 of said lever becomes operative to effect final clamping pressure of said parts.

The end of the bracket 13 remote from the jaws 14 is formed with a short vertical

bearing sleeve 25. Into said sleeve extends a stud 26 which is locked from rotation by a pin 27. Said pin is made integral with a clutch guide plate 28, which is supported by the pin 27 slightly above the upper end of the sleeve 25. The guide plate is thereby fixed to the bracket arm 13. Said plate 28 is provided on its upper face with a plurality of radial shallow grooves 29, three being herein shown, which extend to the margins of said plate. 30, 30 designate a plurality of chuck jaws that are radially disposed relatively to the said guide plate. They are formed on their upper sides with a plurality of can supporting faces 31, and are provided radially outwardly beyond said can supporting faces with inwardly extending lips 32 separated from said faces to form grooves 33 that are adapted to receive and hug the lock seam between the bottom and the body of a can. The said chuck jaws are formed on their inner ends to provide shallow guide ribs 34 which engage the guide grooves 29 so as to guide the jaws truly radially inwardly and outwardly when the latter are operated by the operating means hereinafter described.

36 designates a rotative jaw operating disc. It is provided at its center with an opening 37 which is offset or flanged at its under side in a manner to be seated between the upper end of the bracket arm bearing sleeve 25 and the guide plate 28. It will thus be seen that the plate 36 is centrally held with respect to said sleeve 25 and the bearing stud 26 and also that it is free to turn or rotate on the axis of said stud 26. The said chuck jaw operating disc is provided on its upper face with a rugged marginal upstanding rim 39 and radially within said rim with a lower circular upstanding rib or guide 40 to guidingly engage the edge of the fixed guide plate. The chuck jaws are provided on their lower sides with driving lugs 42 which are adapted to enter short eccentric grooves 43 formed on the upper face of said operating disc 36, and radially located between the guide ribs 40 and the rim 39 of the chuck operating disc.

With the construction described, it will be noted that, when the parts are assembled in the manner shown in Figure 6, with the stud 26 of the fixed guide plate 28 centered in the sleeve 25 and locked thereto by the pin 27, and with the rotating chuck actuating disc rotatively mounted on the upper shouldered end of the sleeve 25, and with the chuck jaws placed with their guiding lugs 34 in the guide grooves 28, and their driving lugs 42 in the eccentric driving grooves 43, rotation of said operating disc 36, as by means of a hand piece 45, will serve to move the chucks inwardly or outwardly, depending upon the direction of rotation of the actuating disc 36, so as to

thereby adjust the chucks closely on the lower ends of the cans to be opened. The presence of the rebates 33 in the chuck jaws between their supporting faces and clamping flanges or lips provides spaces to receive the lock seams at the bottom of the cans, and this relation of the parts effects an interlocking connection between the jaws and cans which aids the clamping pressure of the jaws to hold the cans in place. 75

The cutting mechanism for cutting the head or top of the can thus centered in the machine is made as follows:

47 designates an arm that is hingedly connected by a pin 48 to the top of the post 80 10 and is adapted to be swung upwardly away from and downwardly towards a limited shoulder 49 at the top of said post. When said arm 47 engages said limiting shoulder 49 said arm is in a horizontal position. 85

Said arm 47 is provided at its free end with a vertical bearing sleeve 50. Rotatively mounted in said bearing sleeve is a short shaft 51 that is connected above the arm 47, 90 as by means of a pin 52, with a hand crank 53. 54 designates an enlarged head on the lower end of the shaft 51. The upper face of said head bears against the lower end of the sleeve 50, when the hand lever 53 is locked in place, so as to thereby hold the parts in relative alignment. Said head 54 is provided with a transverse opening 55 to receive a short rod 56 that may be fastened therein by a set screw 57. One end of the 100 rod is formed with a short flanged vertical holder 58 to receive and support a cutting knife 59, the body of said cutting knife being held in place by a screw 60. The flange formation of said head 58 provides lateral 105 shoulders to engage the side edges of the knife, whereby said knife, when clamped on the head by the screw 60, is locked firmly in place relatively to the head. The lower end of the knife is formed to provide a central 110 cutting point 62 and with equilateral cutting edges 63, 63, so arranged that the knife may be revolved in either direction to cut the head from the can by either tapered edge 63. 115

In order to afford a reliable connection of the knife holder rod with the head 51, the said rod may be flattened or otherwise made of irregular cross section to fit a like cross section opening in said head. The rod is 120 shown as formed with a flat face 62 against which the inner end of the clamping screw impinges, as shown in Figures 2, 3, and 4.

By reason of the shiftable connection of the knife holding rod 56 with the head 54 125 of the rotating shaft 51, and its attachment to said head by the set screw 57, it will be observed that said rod may be endwise shifted so as to adjust the machine for cans varying considerably in diameters. The 130

vertical adjustment of the clutch support enables the machine to operate on cans which vary considerably in height. Thus the machine may be said to be universal with respect to both the diameters and heights of the cans to be operated upon.

The lower side of the head 54 is provided with a centering nipple adapted to engage the can head centrally thereof, and to thereby aid to hold the can centered with respect to the cutting knife 59.

I claim:

In a device of the character described, a support having an opening extending through the same, a disk resting on said

support and having a central depression, a circular plate fitting in said depression and having a stem extending through said disk and into the opening in the support, said plate having radial guides in the top thereof, chuck jaws slidable along said guides, said disk having eccentric cam grooves beyond the periphery of said plate, and each jaw having a projection extending into one of said grooves.

In witness whereof I claim the foregoing as my invention, I hereunto append my signature this 27 day of July, 1921.

JOHN THOMAS McGRATH.
